UNITED STATES PATENT OFFICE.

WILLIAM MACINTOSH, OF HAHNS PEAK, COLORADO.

VISIBLE WARNING ATTACHMENT FOR BARBED-WIRE FENCES.

970,524.

Specification of Letters Patent. Patented Sept. 20, 1910.

Application filed August 13, 1909. Serial No. 512,672.

To all whom it may concern:

Be it known that I, WILLIAM MACINTOSH, a citizen of the United States, residing at Hahns Peak, county of Routt, and State of Colorado, have invented certain new and useful Improvements in Visible Warning Attachments for Barbed-Wire Fences; and I do declare the following to be a full, clear, and exact description of the invention, such 5 as will enable others skilled in the art to which it appertains to make and use the same, reference being had to the accompanying drawings, and to the letters and figures of reference marked thereon, which form a 10 part of this specification.

My invention relates to a visible warning attachment for barbed wire fences, adapted for use where animals are brought in contact therewith.

20 The object of my improvement is to prevent injury to animals by coming upon the fence unawares and injuring themselves upon the wires which are usually equipped with harsh barbs.

25 In my improved construction, I equip the posts with a top member, which is of sufficient width to make it visible to the animal, thus causing him to observe it before coming in contact therewith. This top

30 member may be of any desired construction. For instance, it may be made of thin metal secured to the posts and connected with the intermediate stays, to which the ordinary wires are attached, or it may be composed

35 of other material whose opposite, longitudinal edges are bent around stiffening wires, to which barbs may be applied, if desired. Attention is called to the fact that this top member may be either plain or barbed, the

40 main idea being to make the member visible to the animal under all circumstances.

Having briefly outlined my improved construction, I will proceed to describe the same in detail, reference being made to the accompanying drawing, in which is illustrated an embodiment thereof.

45 In this drawing: Figure 1 is a side elevation of a section of fence equipped with my improvement. Fig. 2 is a fragmentary detail view illustrating the top member of the construction shown in Fig. 4, but on a larger scale. Fig. 3 is a section taken on the line 6—6, Fig. 2.

The same reference characters represent 55 the same parts in all the views.

Let the numeral 5, designate the posts and 6, the wires of an ordinary barb wire fence. To the upper portion of the posts, is applied the visible warning member 7, which, as heretofore indicated, may be of any desired 30 construction to make it conspicuous, and prevent the animal from running against the fence and doing himself injury.

If the fence is of such construction that the animal can readily see it, it will of 65 course be avoided by him. In my improved fence, the warning member is usually applied to the upper extremities of the posts, thereby taking the place of the uppermost wire or the uppermost two wires, depending 70 somewhat upon the width of the warning or safety member.

In the form of construction shown, the body 10, of the warning or safety device may be composed of any thin or flexible 75 fabric. Its opposite edges are bent around wires 12, forming a supporting frame for the fabric. While this device may be perfectly plain and smooth, it is illustrated in the drawing equipped with wire barbs 13, 80 which are applied to its upper edges with the stiffening wires 12, forming a support therefor.

While the plain form of the warning member would prevent possible injury by 85 reason of the animal's coming in contact therewith, it is believed that there is no objection to barbs on this warning or safety member, since it is always conspicuous and readily visible to the animal, and under 90 such circumstances, he will keep away from it. It would thus appear that there is no danger to animals from rough barbs, where they are mounted upon a member or members which are sufficiently conspicuous to 95 make them readily visible at all times.

The body of the warning or safety member may consist of a thin ribbon of steel or other material, and its width may vary according to circumstances, the one requirement being that it shall make itself conspicuous at all times for the aforesaid purpose.

Having thus described my invention, what I claim is:

1. A visible warning attachment for barbed wire fences, comprising a top member of conspicuous vertical width, the said member being composed of relatively thin material and stiffening wires, around which 110

its opposite edges are bent, the said edges being equipped with barbs for the purpose set forth.

2. A visible warning attachment for
5 barbed wire fences, comprising a top member of conspicuous vertical width, the said member being composed of relatively thin material, and longitudinally disposed stiffening wires over which its opposite edges
10 are folded, the said edges being equipped

with barbs passing through the folds and around the wires, as means of holding the wires in the folds, substantially as described.

In testimony whereof I affix my signature in presence of two witnesses.

WILLIAM MACINTOSH.
